Fig. 4

Diagram showing a branching structure with labels: 6, 46, 43, 28, 41, and 46. The structure consists of a main horizontal line with a vertical branch on the left and a curved branch on the right. The labels are positioned as follows: '6' is at the start of the main line; '46' is on the vertical branch; '43' is at the top of the curved branch; '28' is on the main line between the vertical and curved branches; '41' is at the end of the curved branch; and '46' is at the bottom of the curved branch.

LUMBER STRAIGHTENING DEVICE

Henry H. Payzant and Paul F. Lueth, St. Paul, Minn., assignors, by mesne assignments, to General Timber Service, Inc., St. Paul, Minn., a corporation of Delaware

Application November 14, 1931
Serial No. 575,035

12 Claims. (Cl. 143—49)

Lumber frequently becomes bowed during the drying subsequent to the sawing into straight pieces and where it is accurately trimmed at both ends to predetermined lengths, each piece should be held, during the trimming, as nearly as possible with its longitudinal edges in perpendicular relation to the trimming saws. Straightening of the lumber is also important during marking, as in cases where spaced lines, extending transverse each piece, are applied to facilitate measurements in construction work.

It is the object of this invention to provide efficient means for eliminating or substantially reducing the longitudinal curve or bow in lumber, during the trimming and/or marking, without greatly increasing the cost of the product.

A further object is to provide a machine of this kind adapted to straighten indiscriminately mixed pieces of lumber which vary in thickness and width, the machine being designed to automatically adjust itself to pieces of differing dimensions.

The invention will be best understood by reference to the accompanying drawings in which: Figure 1 is an end view of a set of the straightening devices mounted on a lumber trimming machine;

Fig. 2 is a transverse section through the trimming machine and showing one of our straightening devices in side elevation;

Fig. 3 is a horizontal section through the straightening device, taken on the line 3—3 of Fig. 2;

Fig. 4 is an end view of the trimming machine with the straightening devices thereon;

Fig. 5 is a fragmentary, vertical section taken on the line 5—5 of Fig. 2;

Fig. 6 is a section taken on the line 6—6 of Fig. 5; and

Fig. 7 is a vertical section taken on the line 7—7 of Fig. 2.

The device is shown in connection with a lumber trimming machine having A shaped end frames 10 connected by longitudinal beams 11 and 12, the beam 12 being mounted to extend above and parallel to a table for the lumber formed by skids 13. Pieces of lumber are indicated in the drawings by the numeral 14. A trimming saw 15 is mounted near each end of the machine to trim the ends of the pieces of lumber which are conveyed edgewise or perpendicular to their greatest dimension by suitable chain conveyers. Each chain conveyer consists of an endless chain 16 trained on sprocket wheels 17 and having its upper run supported on lat-

erally projecting flanges, integral with the skids 13. Each chain 16 has lugs 18 secured thereto at regularly spaced intervals. These lugs project above the upper run of the chain to engage the lumber and the lugs on the several chains are disposed with their lumber-engaging faces in alignment in rows extending perpendicular to the saws 15.

Our straightening device has an endless chain 19 trained on sprocket wheels 20 and 21. At regularly spaced points lugs 22 project from the chain 19, being provided with contact shoes 23 for engaging the lumber. The sprocket wheels 20 and 21 are supported on horizontal shafts 24 and 25 respectively and these shafts have suitable bearings secured to opposite ends of a horizontally extending frame. The main frame members of the frame comprise a large channel member 26 and a parallel angle member 27. These frame members are suspended from hangers 28 having their upper ends projecting through perforations in supporting blocks 29. The hangers 28 are arranged to permit upward movement of the straightening devices when the thicker pieces of lumber pass beneath them. A pair of channel beams 30 are secured to the overhead beam 12 of the main frame and are spaced apart by downwardly extending channel beams 31 and 32, the latter being rigidly fastened to the beams 30 and terminating at their lower ends between the frame members 26 and 27 of the straightening device. Pivotally secured to the lower end of the beam 30 is a pair of link bars 33 which extend substantially horizontally and are connected by a pivot pin 34 to the frame members 26 and 27. By this arrangement of the link bars 33 and pendant beams 31, the frame of the straightening device is allowed freedom for substantially vertical movement, but is prevented from moving longitudinally in the direction of movement of the lumber. The pendant beam 32 constitutes a guide for vertical movement of the rear end of the frame.

Fixed on the horizontal shaft 25 is a brake drum 35 and cam 36. To engage the periphery of the brake drum, a brake band 37 is provided. At one end this band is secured to an angle bar 38 constituting part of the frame and the other end of the band has secured thereto a flange member 39 which is perforated to slidably engage a vertical rod 40. The lower end of the rod 40 has a head engaging the bar 38 and said rod extends above the member 39 and has a spring 41 confined theron to normally actuate the brake band to operative position relative to the drum. A pivot

shaft 42 extends parallel to the shaft 25 and is mounted in suitable bearings on the frame members 26 and 27. Pivoted on this shaft 42 is a tubular member 43 having an integral pair of arms 44 carrying a roller 45 to be actuated by the cam 36. A second pair of arms 46 project from the member 43 at opposite sides of the spring 41 to actuate a U-shaped rod 47 which passes beneath the member 39 and has its ends bent outward to engage the arms 46 in suitable perforations therein. It will be understood that the cam 36 is formed with a projection arranged to actuate the roller 45 periodically, so that the brake band 37 is loosened by the action of the arms 44 and 46 and rod 47 in raising the member 39 against the spring 41. The lower reach of the chain 19 is prevented from bending upward, out of a straight line, by a guide bar 49 of angular cross section.

20 In operation, a shaft 17a for supporting and driving the sprocket wheels 17, is driven by suitable connections with a motor. A sprocket wheel 48 on one end of the shaft 17a may be employed for the power connection so that the chains 16 are continuously driven in the direction indicated by arrows in Figs. 2 and 4. Each piece of lumber to be trimmed is laid across the skids 13 at the receiving side of the machine and is picked up and carried along the skids by a row of the lugs 18 on the chain 16. Three of the straightening devices are preferably used, as indicated in Fig. 1, one of these devices being located near the middle point of the beam 12 and the other two near the trimming saws 15. The several straightening devices are disposed in alignment longitudinally of the lumber so that a set of three of the lugs attached to the chains 19 engages each piece of the lumber. As a piece of lumber is carried beneath the chains 19 it strikes a set of the shoes 23 on the lugs 22 and actuates the chains 19, together with the sprocket wheels 20 and 21, brake drums 35 and cams 36. During a greater part of the movement of each chain 19 in engagement with the lumber the brake band is held in operative relation to the drum 35 by the spring 41 so that the straightening device has a forceful retarding or backward thrust on each piece of lumber. This backward thrust is sufficient to straighten pieces of lumber which are bowed longitudinally and is so distributed by the three devices that it is effective whether the bow of a particular piece is away from the lugs 18 near the middle of a row, or near the end lugs 18. The straightening force is applied to each piece during its travel past the saws but as the piece approaches the end of the lower reach of the chain 19, the cam 36 reaches a position where it actuates the roller 45 and, through the connections with the brake band, releases the brake against the spring 41. This allows the chain 19 to move freely while one piece of lumber is passing out of engagement with the lugs 22 and while the succeeding piece is moving into proper engagement with the succeeding lugs 22. The weight of the straightening device is sufficient to prevent the lumber from moving laterally or vertically out of the path of the lugs 18 and 22 and, as hereinbefore described, the frame supporting the chain 19 is movable vertically to permit the passage of pieces of lumber of various thicknesses between the lower reach of said chain and top of the skids 13.

Obviously the operation of straightening the lumber takes place simultaneously with the trimming and does not substantially increase the cost of manufacture. Our device is adapted for use

with machines other than that illustrated and has been used successfully in the manufacture of lumber which is marked at regularly spaced intervals, as by foot and inch marks extending transverse the greatest dimension.

Having described our invention, what we claim is:

1. A straightening device for lumber having in combination means for moving pieces of lumber edgewise and in spaced relation to each other along a determined path, an endless chain having one of its reaches extending in parallel relation to the direction of movement of the lumber, lugs projecting from said chain to engage the front edges of said pieces and friction means for retarding said chain to forcibly straighten the lumber edgewise by rearward bending of the same, said chain being arranged to be actuated by engagement with the moving lumber.

2. A straightening machine for lumber having in combination means for moving lumber along a determined path, a retarding device extending in parallel relation to the direction of movement of the lumber, means projecting from said device in the path of the lumber, friction means for retarding said device to forcibly straighten the lumber, said device being arranged to be actuated by engagement with the moving lumber and means for actuating said friction means to reduce the friction.

3. A lumber straightening device having in combination a lumber receiving table, means for moving lumber upon said table in a direction transverse the greatest dimension of the lumber, a plurality of endless chains having lugs projecting into the path of the lumber on said table, said chain being movable by engagement of said lugs with the lumber, a brake for retarding each of said chains and means for periodically actuating said brakes to allow free movement of said chains.

4. In a lumber straightening device, a pair of sprocket wheels, an endless chain trained on said wheels, spaced projections on said chain for engaging lumber, a shaft operatively connected to one of said sprocket wheels, a brake drum on said shaft, a friction band on said drum, means for actuating said band to grip said drum, a cam on said shaft and means operatively connecting said cam to said friction band for periodically releasing said drum.

5. A lumber straightening device having in combination a lumber receiving table, means for actuating lumber upon said table in a direction transverse the greatest dimension of the lumber, a plurality of endless chains having lugs projecting into the path of the lumber on said table whereby said chains may be actuated by engagement with the lumber, friction means operatively connected to each of said chains, spring means for actuating said friction means to retard said chains, a cam operatively connected to each of said chains and means operatively connecting said cams to said friction means for periodically releasing said chains.

6. In a machine for forcibly straightening curved pieces of lumber, a conveyer adapted to forcibly move separate pieces of lumber along a determined path, means fixed on said conveyer for engaging the rear of each piece of lumber, said engaging means extending in a straight line perpendicular to the direction of movement of the conveyer, a friction retarded device movable a substantial distance along said path adjacent to said conveyer and a projection on said retarded

device adapted to positively engage the front surface of a piece of lumber on said conveyer, said projection being movable a substantial distance along said conveyer to bend the lumber rearwardly 5 and thereby straighten the same.

7. In a machine for forcibly straightening curved pieces of lumber, a conveyer having lumber-engaging means spaced longitudinally of the conveyer to advance pieces of lumber in parallel, 10 widely spaced relation to each other along the determined path, a retarding device movable a substantial distance along said path adjacent to said conveyer and a lug projecting from said retarding device into the path of said lumber, said 15 lug being arranged to engage a piece of lumber on said conveyer to bend it rearwardly and being movable in operative position along said conveyer a distance not greater than the spacing of said lumber-engaging means along the conveyer.

20 8. A lumber straightening device having in combination, a conveyer for moving pieces of lumber in spaced, parallel relation to each other along a determined path, a plurality of retarding devices spaced apart longitudinally of the lumber 25 and movable in parallel relation to the direction of movement of said conveyer, each of said retarding devices having a lug projecting to positively engage the front surface of a piece of lumber on said conveyer and said retarding devices being independently mounted so that movement 30 of one of them does not affect the movement of another of said devices and power-driven means for actuating said conveyer to forcibly advance the pieces of lumber successively into engagement with said retarding devices.

35 9. In a machine for forcibly straightening curved pieces of lumber, a plurality of conveyer chains each having a reach extending in a common plane with a reach of the other chains, lugs fixed on said chains for engaging the rear of each piece of lumber, said lugs extending in a straight line perpendicular to the direction of movement of the chains, a friction retarded device movable a substantial distance in parallel relation to said 40 reaches of the chains, a projection on said retarded device adapted to positively engage the front surface of a piece of lumber carried by said chains and power-driven means for actuating said chains in unison, said projection being movable a substantial distance along said chains to 45 bend the lumber rearwardly and thereby straighten the same.

10. A machine having in combination, means for treating lumber and means for forcibly straightening curved pieces of lumber during the operation of said treating means, said straightening means comprising a conveyer adapted to move 80 pieces of lumber in spaced, parallel relation to each other along a determined path to and from said lumber treating means, a retarding device movable a substantial distance along said path adjacent to said conveyer and a projection on said retarding device formed to positively engage a piece of lumber on said conveyer and movable a substantial distance along said conveyer to bend the lumber rearwardly and to retain the lumber 85 in rearwardly bent position during the operation of said treating means.

11. A machine having in combination, means for trimming the ends of lumber and means for forcibly straightening laterally curved pieces of lumber during the operation of said trimming means, said straightening means comprising a conveyer adapted to move pieces of lumber in spaced, parallel relation to each other along a determined path adjacent to said trimming means, a retarding device movable a substantial 95 distance along said path adjacent to said conveyer and a projection on said retarding device formed to positively engage the front surfaces of pieces of lumber on said conveyer and movable a substantial distance along said conveyer to bend 100 the lumber rearwardly and to retain the lumber in rearwardly bent position during the operation of said trimming means.

12. In a machine for forcibly straightening laterally bent pieces of lumber, a conveyer adapted 110 to forcibly move lumber edgeways along a determined path, means fixed on said conveyer for engaging the rear edge of the lumber and extending in a straight line perpendicular to the direction of movement of the conveyer, a friction retarded device movable a substantial distance along said path adjacent to said conveyer and means on said retarded device adapted to 115 positively engage a piece of lumber on said conveyer, said engaging means being movable a substantial distance along said conveyer to bend the lumber rearwardly and thereby retain the same 120 in straightened form during a substantial portion of the travel of said conveyer.
